UNITED STATES PATENT OFFICE.

STANLEY MACOMBER, OF MASSILLON, OHIO, ASSIGNOR TO THE MACOMBER STEEL COMPANY, OF CANTON, OHIO, A CORPORATION OF OHIO.

BAR-BENDING MACHINE.

Application filed September 21, 1925. Serial No. 57,608.

The present improvements relate more particularly to mechanism for bending a rod or bar in opposite directions so as to put a 2-bend offset in such a rod or bar, both bends being in the same plane and the angles thereof being the same so as to leave the offset portion parallel to the main body of the bar. Bars with their ends thus bent are variously used as web-members in trusses and truss-like structural units as well as for other purposes such as the reinforcing of concrete walls, etc.

It has been found impracticable to employ a bulldozer for the purpose indicated since this involves taking a die the shape of the desired bend and then forcing the straight bar into position; this for the reason that an operation such as the one just described will cause at least one end of the bar to be drawn over one point of the die and as a result the bar will be continually pulled through an arc, first bending and then straightening. Such treatment of the bar obviously reduces its strength for structural purposes.

The object, accordingly, of the present improvements is to provide a mechanism adapted actually to bend the bar at the point of bend, keeping that part of the bar between bends always straight, and to this end, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a plan view and Fig. 2 a side elevation of one type of machine constructed to bend rod or bar stock in accordance with my present improved method; Figs. 3 and 4 illustrate more or less diagrammatically the operation of such machine; Figs. 5 and 6 are respectively a plan view and side elevation of another form of machine designed to operate in substantially the same fashion as such first type of machine; and Fig. 7 is a sectional view of a detail of such second machine, the plane of the section being indicated by the line 7—7, Fig. 5.

The machine illustrated in Figs. 1 and 2, so far as its general framing and driving is

concerned includes a horizontal table 1, in the center of which is located a small horizontal cast plate 2 that is adapted to be rotated by lever control in one direction and reversed by hand. The details of the mechanism by which such plate is thus adapted to be rotated form no part of the present invention and it will accordingly suffice to note that such plate is mounted on the upper end of a vertical shaft 3 that projects through an opening in the table 1 and that for the purpose of rotating the shaft and plate in a clockwise direction, as viewed in Fig. 1, said shaft may be clutched to a suitable driving gear 4, while a hand lever 5 is provided to rotate it in the opposite direction.

Bolted to the table top are two parallel blocks 6 and 7 between which the bar to be bent is placed. These blocks are preferably adjustably secured to the table by having transversely elongated slots through which the securing bolts 6^a and 7^a pass so as to permit transverse adjustment in order that, irrespective of the size or diameter of the bar held therebetween, the center of such bar may be directly over the center of the rotating plate 2.

Supported upon the rotatable plate 2 is a radially projecting arm 10 which is similarly secured to said plate by means of bolts 11, passing through slots in the arm, so that the latter may be bodily adjusted transversely of the center of the plate. The latter is provided adjacent its forward face with an undercut groove 12 in which are adjustably slidably held two blocks 13 and 14. The first of these blocks will normally be located closely adjacent the inner end of the arm, i. e., the center of plate 2, while the location of the outer block 14 will be varied, dependent upon the length of the rod or bar between successive bends. Secured to the table top so as to face said arm 10 is a stop 15 that has a horizontally extending face, said stop being carried by brackets 16 on a slide 17 that is adjustably secured by means of bolts 18 to parallel undercut slots 19 in such table top.

In operation, assuming a rod or bar R (see Fig. 3) to be placed between the blocks or jaws 6 and 7 so as to allow a suitable length thereof to project alongside arm 10, and assuming the blocks 13 and 14 on the

- latter to be correctly positioned, the arm is swung in a counter-clockwise direction by rotating shaft 3 and plate 2. The first effect of such rotation will be to bend the projecting portion of the bar at the point where it leaves the blocks 6 and 7 until such projecting portion assumes the position shown in dotted outline in Fig. 3. However, before such first bend is completed, the block 14 will start a second bend as it forces such projecting portion of the rod against stop 15. Both bends will be completed (see Fig. 4) as said block 14 on arm 10 finally pinches the bar against the stop 15, the travel of the arm being stopped as for example by an automatic trip when this stage in the operation is reached. Thereupon the arm is rotated back into its original position by hand.
- 20 The machine illustrated in Figs. 5, 6 and 7, so far as its general structure is concerned, is analogous in framing and supports to the type of machine shown in Figures 1 and 2. However, the center of rotatable plate 20 25 here lies flush with the top of the table 21 and is designed to be power rotated in both directions subject to hand control. Two parallel bars 22 are secured to the top of the table by means of bolts 23 that pass through slotted holes in said bars so as to permit their adjustment in a fashion similar to that of blocks 6 and 7. Directly secured to the rotating plate 20 is an arm 24 of the cross-sectional form shown in Fig. 7, 30 and slidably adjustably secured on said arm are two blocks 25 and 26. A stop plate 27 is mounted on the table top, said stop being adjustable at right angles to the line of the opening between bars 22.
- 35 The operation of this second form of machine is substantially the same as that of the first form, such operation being clearly indicated by the showing in dotted outline of the positions successively occupied by the projecting rod end in Fig. 5.
- 40 In both types of machine it will be observed that the two bends of the bar are accomplished by one motion, also that the bends leave the offset portion or extremity 45 of the rod parallel with the main body of the latter. Bars ranging from $\frac{3}{8}$ inch diameter to $\frac{1}{16}$ inch diameter may be readily bent in the fashion thus described on the foregoing machines with bends varying from 50 55 8 inches to 12 inches in their distance apart from each other, while the terminal or offset portion may be of variable length up to 10 inches. Obviously the machine is not limited to operation with rod of any particular dimension, the foregoing dimensions and 60 65 lengths being merely illustrative.
- Other modes of applying the principles of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. In mechanism of the character described, the combination of a pair of parallel blocks adapted to grip a length of bar therebetween; an arm oscillatorily mounted about an axis adjacent one end of said blocks; two blocks relatively adjustably mounted on said arm and adapted to contact at longitudinally spaced points with a portion of such bar projecting beyond said first-named blocks; and a stop located in the path of travel of the outer of the blocks on said arm and having a stop-face lying substantially parallel with said gripping blocks.

2. In mechanism of the character described, the combination of a pair of parallel blocks adapted to grip a length of bar therebetween; an arm oscillatorily mounted about an axis adjacent one end of said blocks; two blocks relatively adjustably mounted on said arm and adapted to contact at longitudinally spaced points with a portion of such bar projecting beyond said first-named blocks; and a stop located in the path of travel of the outer of the blocks on said arm and presenting an elongated face against which such projecting bar-portion may be pressed by said block.

3. In mechanism of the character described, the combination of a pair of relatively adjustable parallel blocks adapted to grip a length of bar therebetween; an arm oscillatorily mounted about an axis adjacent one end of said blocks; blocks independently adjustably mounted on said arm and adapted to contact at longitudinally spaced points with a portion of such bar projecting beyond said first-named blocks; and a stop located in the path of travel of the outer of the blocks on said arm, and presenting an elongated face against which such projecting bar-portion may be pressed by said block, such stop-face lying substantially parallel with said gripping device.

4. In mechanism of the character described, the combination of a stationary device adapted to grip a length of bar; a member oscillatorily mounted about an axis adjacent one end of said device; two blocks mounted on said member and adapted to contact during a single movement of said member at longitudinally spaced points with a portion of such bar projecting beyond said device to give such projecting portion of the bar an angular formation; and a stop located in the path of travel of said bar and one of said blocks thereby to give the extreme bar end a formation relatively angular to that of the intermediate part of said projecting bar portion.

5. In mechanism of the character described, the combination of a stationary device adapted to grip a length of bar; a member oscillatorily mounted about an axis adjacent one end of said device; two blocks 5 mounted on said member and adapted to contact at longitudinally spaced points with a portion of such bar projecting beyond said device; and a stop located in the path of 10 travel of said bar and having a stop-face lying substantially parallel with said device, thereby to give the extreme bar end an angular formation parallel to that of the bar portion gripped by the device.

15 6. In mechanism of the character described, the combination of a stationary de-

vice adapted to grip a length of bar; a member oscillatorily mounted about an axis adjacent one end of said device; two relatively adjustable blocks mounted on said member 20 and adapted to contact during a single movement of said member at longitudinally spaced points with a portion of such bar projecting beyond said device; and a stop located in the path of travel of the outer of 25 said blocks and having an elongated stop-face, thereby to give the extreme bar end a formation relatively angular to that of the intermediate part of the projecting bar portion. 30

Signed by me this 18 day of Sept., 1925.

STANLEY MACOMBER.
